UNITED STATES PATENT OFFICE.

SAMUEL MARTIN TAYLOR AND ALBERT DAVID OSBORN, OF BLAIRSDEN, CALIFORNIA.

CIRCULAR-SAW MACHINE.

1,273,422.

Specification of Letters Patent. Patented July 23, 1918.

Application filed June 13, 1917. Serial No. 174,565.

To all whom it may concern:

Be it known that we, SAMUEL M. TAYLOR and ALBERT D. OSBORN, citizens of the United States, residing at Blairsden, in the county 5 of Plumas and State of California, have invented certain new and useful Improvements in Circular-Saw Machines, of which the following is a specification, reference being had to the accompanying drawings.

10 It is an object of the invention to provide a circular saw machine embodying novel and improved means whereby the work or stock may be guided with respect to the saw or saws.

15 It is also an object of the invention to provide a device of this general character having a novel and improved work guide including relatively movable guide members between which the work or stock passes 20 with the minimum of frictional resistance and wherein the relative movement of the members compensates for any unevenness in the stock or work so that no hindrance or interference will be encountered during the 25 sawing operation.

Figure 1 is a view in elevation illustrating a circular saw machine constructed in accordance with an embodiment of our invention;

30 Fig. 2 is a view in top plan of the device as disclosed in Fig. 1;

Fig. 3 is a sectional view taken substantially on the line 3—3 of Fig. 1;

Fig. 4 is a sectional view taken substantially on the line 4—4 of Fig. 2;

Fig. 5 is a sectional view taken substantially on the line 5—5 of Fig. 1;

Fig. 6 is a sectional view taken substantially on the line 6—6 of Fig. 1; and

40 Fig. 7 is a view partly in elevation and partly in section illustrating the mounting for the saws as herein disclosed.

As disclosed in the accompanying drawings and as herein embodied, 1 denotes a horizontal bed or table supported at a predetermined elevation through the medium of end plates 2. The bed 1 is provided with an elongated slot or opening 3, one longitudinal marginal portion of which being defined by 45 a movable plate or supplemental bed 4. As herein disclosed the opposite end portions of the plate or supplemental bed 4 rest upon

shoulders 5 produced transversely of the opposed faces of the end plates 2. The plate or supplemental bed 4 is adapted to be 55 moved along the shoulders 5 in order that the width of the opening or slot 3 may be regulated.

The opposed faces of the end plates 2 are provided with a plurality of pairs of vertically alined and inwardly directed lugs 6, and rotatably supported by each pair of lugs 6 is a threaded shaft 7 operatively engaged with an end portion of a horizontally disposed beam 8. The outer beam 8 65 adjacent the opening or slot 3 has its intermediate portion 8^a removable for a purpose which will hereinafter be more particularly referred to. The lower end portions of the shafts 7 carried by each of the end plates 70 2 are operatively engaged, as indicated at 9, with a transversely disposed shaft 10 rotatably supported by the end plate 2.

The shafts 10 extend beyond corresponding sides of the end plates 2, and said extended portions are provided with sprockets 11, with which an endless sprocket chain 12 is operatively engaged. By this arrangement it will be perceived that the shafts 10 will be caused to rotate in unison and in the 80 same direction in order to effect a raising or lowering of the beams 8. While the requisite rotation of the shafts 10 may be obtained by a desired pull upon the chain 12, it is to be understood that a mechanical 85 means may be employed if desired for driving the chain 12.

The central portions of the beams 8 are provided with longitudinally disposed slots 14 which permit an adjustable mounting on 90 said beams 8 of the bearings 15. Rotatably supported by the bearings 15 is a mandrel 16 having affixed thereto a pulley 17 adapted to be coupled with a suitable source of power. Also affixed to the mandrel 16 in a 95 position below the opening or slot 3 of the bed 1, is a drum 18 of a relatively large diameter, and preferably of a diameter substantially one-half that of the saw or saws 100 S mounted upon the drum 18. The diameter 100 of the drum 18 permits the use of a comparatively thin saw and a saw having a large major diameter. By having a comparatively thin saw a material saving of

- stock is effected, while the large diameter of the saw affords an increased cutting circle which in practice has been found to result in an extremely smooth cut.
- 5 The saws S are maintained in predetermined spaced relation through the medium of rings or collars 19 interposed between the saws, and said saws S are clamped upon the drum 18 through the medium of a collar 20
- 10 in threaded engagement with the outer end portion of the drum 18 and which coacts with an annular flange 21 positioned at the inner end portion of the drum. A portion of the collar 20 is provided with a circumferentially disposed series of spaced recesses 22, to afford a means whereby a spanner or other implement may be readily engaged with said collar 20 in order to apply or remove the same.
- 15 20 When it is desired to apply or remove a saw or saws, the beams 8 are preferably moved to their lowermost position. The intermediate portion 8^a of the outer beam 8, and if desired the plate or supplemental bed 25 4, are removed. Convenient access can then be had to the collar 20 to effect its removal, and after the collar 20 has been removed a saw or saws S can be easily taken off and replaced.
- 20 30 While we herein disclose the saws as arranged in a gang of five, we do not wish to be understood as limiting ourselves to this exact number, as any number of saws may be employed within the scope of the machine. An end portion of the bed 1 is provided with a transversely disposed guideway 23 extending a predetermined distance beyond the supplemental bed or plate 4. Within the guideway 23 is a slide member 24
- 35 40 provided at its outer end with an upstanding flange 25 and a depending flange 26. The opposite ends of the guideway 23 are closed, and in swivel connection with the outer end 27 of the guideway 23 is a threaded member 28 disposed through the depending flange 26. By this arrangement it is perceived that by rotating the member 28 the slide 24 is caused to move longitudinally of the guideway 23. As herein embodied the
- 45 50 outer end portion of the member 28 has co-acting therewith a ratchet lever 29, operating in a well known manner to rotate the member 28.
- 55 The inner end portion of the slide 24 is provided with an upstanding bracket 30, which rotatably supports the rollers 31 arranged in predetermined spaced relation transversely of the guideway 23, with the axes of said rollers 31 vertically disposed.
- 60 65 60 The upper face of the slide 24 intermediate the bracket 30 and the upstanding flange 25 is provided with a guideway 32 with which is movably engaged a supplemental slide 33. The inner portion of the slide 33 is also provided with an upstand-
- ing bracket 34 which rotatably supports the rollers 35, also spaced transversely of the guideway 23 with their axes vertically disposed. The forward end of the slide 33 is provided with an upstanding flange 36, and interposed between the flanges 25 and 36 is an expandible member 37, which tends to constantly urge the slide 33 toward the inner end of the slide 24.
- The stock or work as indicated by dotted lines at W in Figs. 1 and 2, is adapted to be disposed between the brackets 30 and 34, and it will be at once self-evident that the contact of the stock or work with the rollers 31 and 35 permits an advance of the work or stock toward the saws S with slight frictional resistance. It will also be understood that the member 37 permits the slide 33 to have such movement as to compensate for any unevenness in the stock or work, and so that any such unevenness in the stock or work will not hinder or interfere with a sawing operation.
- The bracket 30 has integrally connected therewith a guide plate 38 which extends over the bed 1 at a point inwardly of the opening or slot 3, and which serves as a guiding means for the work or stock. The position of the plate 38 relative to the slot or opening 3 can be readily adjusted by the slide 24.
- Seated within the end portion of the opening or slot 3 back of the saws S is a block 39 provided with upstanding splitters or arms 40, of a thickness substantially equal to the thickness of the saws S and arranged in alignment with said saws S. The arms or splitters 40 are also inclined toward the saws S and partly overlie the same, as is disclosed particularly in Figs. 1 and 2. The arms or splitters 40 extend within the cuts in the stock or work and thereby serve to hold the stock or work from striking back of the saws.
- I claim:
1. A circular saw machine consisting of a bed provided with an opening, a saw supported below the bed and adapted to extend through the opening of the bed, a guideway arranged adjacent one end of the slot and disposed transversely thereof, a slide movable within the guideway, means for imparting movement to the slide longitudinally of the guideway, a second slide movably mounted upon the first named slide, work engaging means carried by adjacent ends of the slides, means for constantly urging one of the slides in one direction independently of the second slide, and a guide plate carried by the second slide and extending over the bed.
2. A circular saw machine consisting of a bed provided with an opening, a saw supported below the bed and adapted to extend through the opening, a guideway arranged adjacent one end of the slot and disposed

transversely thereof, a slide movable within the guide way, a second slide movably mounted upon the first named slide, work engaging means carried by the slides, and an 5 expandible member coacting with the slides for constantly urging the second named slide in one direction.

In testimony whereof we hereunto affix our signatures in the presence of two witnesses.

SAMUEL MARTIN TAYLOR.
ALBERT DAVID OSBORN.
